CLAIM

The ornamental design for a combined barrel tip assembly and point unit for a writing instrument, as shown and described.

DESCRIPTION

FIG. 1 is a front elevational view of a point and barrel tip assembly for a writing instrument showing my new design;

FIG. 2 is a right side elevational view thereof;

FIG. 3 is a rear elevational view thereof;

FIG. 4 is a bottom plan view thereof on an enlarged scale;

FIG. 5 is a front elevational view of the point showing same separate from the barrel assembly for convenience of illustration;

FIG. 6 is a right side elevational view thereof;

FIG. 7 is a rear elevational view thereof; and

FIG. 8 is an enlarged scale bottom plan view thereof. The broken lines indicated in FIGS. 1-4 have been shown for illustrative purposes only.
